UNITED STATES PATENT OFFICE.

EDWARD KENER, JR., OF BUFFALO, NEW YORK, ASSIGNOR TO BUFFALO CO-OPERATIVE STOVE CO., OF BUFFALO, NEW YORK, A CORPORATION OF NEW YORK.

INCINERATOR.

Application filed July 18, 1924. Serial No. 726,730.

This invention relates to an incinerator which is more particularly intended for use in hospitals and similar establishments in which paper receptacles which receive the spittle of patients, and other medical or surgical devices used in connection with the sick are to be destroyed so as to prevent the spread of disease or contagion.

It is the object of this invention to provide an incinerator having this capacity which is of simple and durable construction, into which the material to be destroyed can be readily and conveniently deposited and from which the residue of the material can be easily and conveniently removed after the same is destroyed and which is so organized that the gases or combustible vapors generated by the material under treatment will be completely consumed and assist in the operation of drying any of the material which may be moist or wet, and which can be operated by a minimum consumption of fuel.

In the accompanying drawings:

Figure 1 is a vertical longitudinal section of an incinerator embodying my improvements showing the incinerator pot in its operative position.

Figure 2 is a similar view showing the incinerator pot in a position which it occupies when removing the residue or destroyed material therefrom.

Figure 3 is a horizontal section taken on line 3—3, Figure 1.

Figure 4 is a fragmentary vertical transverse section taken on line 4—4, Figure 1.

Similar characters of reference indicate like parts throughout the several views.

The numeral 10 represents the combustion chamber of the incinerator, the upright walls of which are provided with an insulating jacket 11 so as to confine the heat therein and the lower end thereof being provided with an air inlet 12 which may be controlled by a movable damper 13, and the top of this chamber communicating with a smoke flue 14 which leads upwardly from the top thereof to the exterior of the building either by means of a chimney or otherwise.

Within the combustion chamber and between the upper and lower ends thereof the same is provided with an inner lining 15 which is generally of cylindrical form and separated from the wall of the combustion chamber by an intermediate air space or passage 16 so that air can pass not only up-

wardly from the lower end of the combustion chamber to the top thereof and through the space within this lining, but also through the passage 16 between the outer side of this lining and the inner side of the combustion chamber. At its lower end this lining rests upon a flange or shelf 17 arranged on the lower part of the inner side of the combustion chamber which shelf or ledge is provided with openings 18, whereby communication is established between the lower part of the combustion chamber and the passage 16.

Within the lower part of the incinerator lining 15 is arranged a pot 19 which is adapted to receive the material to be destroyed. This pot is open in the top for the reception of the material to be destroyed and has a cylindrical side wall 20, a closed bottom 21, and an upright flue or tube 22 of upwardly tapering form which extends upwardly from the bottom of the pot and terminates at its upper end below the top or upper edge of the pot, both the lower and upper ends of this flue being open. The material to be destroyed is introduced into the upper end of this pot through an inlet opening or passage 23 which is formed in the upper front part of the wall of the combustion chamber, which inlet opening is normally closed by means of a door 24 which is connected at its lower end by means of a pivot with the adjacent part of the wall of the combustion chamber.

Within the lower part of the combustion chamber and adjacent to the underside of the incinerator pot is arranged the burner whereby a gaseous flame is delivered upwardly into the flue, this burner consisting of a delivery pipe 26 arranged horizontally and lengthwise and extending through the front wall of the combustion chamber where it is connected with a gas supply pipe 27 and provided with a controlling valve 28 while the inner end of this pipe is provided with a shank 29 which rests on a ledge 30 and the intermediate part of the same is provided with an upwardly projecting nozzle 31 whereby the gas is directed from the delivery pipe 26 upwardly into the flue 22.

Above the upper end of the flue and arranged at a distance therefrom is a deflector 32 which is constructed of upwardly tapering or conical form and is of larger diameter than the upper end of the flue so that the

gaseous flame issuing from the upper end of the flue is deflected laterally in all directions over the refuse or other matter which has been deposited within the pot for cremation. 5 This deflector may be supported in any suitable manner, but preferably by means which comprise a horizontal cross bar 33 extending across the upper end of the flue and secured at its opposite ends in openings in this flue 10 by casting this flue upon this bar after the latter has been previously placed in the mold whereby the flue is produced, and an upright stem 34 rising from the central part of the cross bar 33 and having an upper screw 15 threaded end which engages with the correspondingly threaded opening in the center of the deflector 32 and a clamping nut 35 arranged at the upper end of the stem 34 and bearing against the upper end of the deflector. The upper edge of the pot is provided with a laterally projecting flange 36 which engages with the inner side of the adjacent part of the lining 15, this flange being provided with a plurality of notches 20 25 37 which are arranged in an annular row thereon and serve to place the space within the lining 15 above and below the upper edge of the pot in communication with each other so that air is free to pass upwardly through 30 the space between the pot and the lining 15 and mingle with the vapors passing off from the top of the pot into the smoke pipe or outlet flue 14.

For the purpose of permitting the residue 35 or ashes of the material which has been cremated or destroyed in the pot to be easily removed therefrom, the pot is pivotally mounted within the combustion chamber so as to permit of tipping the upper end of the 40 same forwardly and downwardly so that the residue can be raked out forwardly and laterally from the pot. For this purpose the pot is provided on its transversely opposite sides with two pivot pins or trunnions 38 45 which are journaled in horizontal bearings 39 arranged on the adjacent parts of the lining of the combustion chamber as best shown in Figures 3 and 4, these trunnions being arranged about midway of the height 50 of the pot and forwardly of a diametrical line extending transversely through the axis of the pot so that the weight of the latter will constantly tend to swing the same into its normal upright operative position, shown 55 in Figure 1. For the purpose of arresting the rotary motion of the pot under the action of gravity during which its upper end moves backwardly and its lower end forwardly, the flange 36 is so constructed that the rear edge 60 portion of the same engages with the rear part of the lining 15, as shown in Figures 1 and 3 so that the cooperation of these parts will serve as stops to limit the swinging motion of the pot when the same has reached 65 its normal upright position.

To permit of such swinging of the pot and still allow the burner to be arranged comparatively close to the lower side of the pot for properly delivering the gaseous fuel into the flue 32 thereof, the underside or bottom 70 of the pot is provided with a horizontal longitudinal channel 40 which communicates with the lower end of the flue 22 and receives the adjacent part of the gas delivery pipe 26 and still permits the pot to turn without interfering with this burner pipe. 75

When it is desired to empty the pot after burning a certain quantity of material and reducing the same to ashes the lower front section 41 of the lining 15 is removed so as 80 to form an opening in this lining and a door 42 which normally closes an outlet opening in the wall of the combustion chamber in line with the door 42 is also opened so that upon tipping the top downwardly and forwardly after the lining section 41 and door 42 have been opened, as shown in Figure 2, it is possible for the attendant to shovel or rake out the residue or ashes from 85 the pot into a receptacle for the purpose of 90 emptying the pot, this operation being accomplished easily and with facility after which the pot can be swung upwardly into its normal position and the doors 41 and 42 closed preparatory to resuming the normal 95 operation of the apparatus. The outer door 42 is preferably constructed in two sections, as shown in Figure 3 which are adapted to swing on vertical hinges connecting the opposite outer edges of the same to the adjacent stationary part of the wall of the combustion chamber. The inner door section 41, however, is removed bodily when not required and is held in its operative position 100 by means of a fastening consisting preferably of a turn button 43 arranged on the upper end of this door section 41 and engaging with a lip 44 on the fixed part of the lining 15 immediately below the lower end of the inlet opening 23. 105

In the operation of this apparatus the heat of the burning gaseous flame issuing from the nozzle 31 by engaging with the inner side of the flue 22 operates to dry the material within the pot throughout the height 110 thereof whereby the gaseous constituents of this material which are generated and liberated during this time are caused to pass upwardly to the top of the mass of refuse. Upon reaching the space within the pot above the top of the refuse, these gases are intercepted by the gaseous flame which issues from the upper end of the flue 22 and is directed in the form of an umbrella in all directions over the top of the refuse whereby 115 the combustible gases liberated from the refuse are ignited and completely consumed before they escape from the top of the combustion chamber through the smoke pipe 14 to the outer atmosphere, thereby preventing 120 125 130

the spreading of any objectionable odors to the exterior of the building which might offend the neighborhood. The consumption of these combustible vapors which are given off from the refuse within the pot is further promoted by the admixture therewith of the air which passes from the lower part of the combustion chamber upwardly through the space between the pot and the lining 15 and 5 the space or passage between the lining and the outer wall of the combustion chamber which air mingles with these combustibles gases immediately above the upper end of the pot and also above the upper edge of the lining 15 and not only dilute these combustible vapors, but also put the same in the best condition for consumption by the flame issuing from the upper end of the flue 22 and 10 directed laterally over these combustible vapors by means of the deflector. It will therefore be apparent that by means of this apparatus the refuse which is deposited in the pot is not only thoroughly consumed and 15 reduced to inert ashes so as to prevent the spread of disease, but it also disposes of this refuse in a manner which is practically odorless and in no wise offensive to inhabitants 20 of the surrounding neighborhood.

I claim as my invention:

30 1. A refuse incinerator comprising a combustion chamber, an imperforate pot having a closed bottom and sides and an open top and pivotally mounted within said chamber so as to be capable of moving into a normal upright position in which the same receives 35 and holds the material to be destroyed or inclined so that its top opens laterally for discharging the contents of the pot, and a burner arranged below the pot, said chamber being provided in the upper part of its enclosure with an inlet door which permits of 40 introducing material into the pot and a discharge door in the lower part of said enclosure for permitting removal of the residue 45 from said pot.

2. A refuse incinerator comprising a combustion chamber provided internally on opposite sides with bearings, an imperforate pot arranged within said chamber, and provided on opposite sides with trunnions journaled in said bearings so that the pot is capable of turning about a horizontal axis, and a burner arranged below said pot, said trunnions being arranged in front of a vertical line extending transversely and diametrically through said pot, and the rear parts of 50 said pot and chamber being provided with cooperating stop surfaces which limit the 55

rearward movement of said pot beyond its normal upright position. 60

3. A refuse incinerator comprising a combustion chamber, an imperforate pot arranged in the combustion chamber and adapted to receive the material to be destroyed and provided centrally with a flue 65 which is open at its lower and upper ends and terminates at its upper end below the upper end of the pot, and a burner arranged at the lower end of said flue. 70

4. A refuse incinerator comprising a combustion chamber, an imperforate pot arranged in the combustion chamber and adapted to receive the material to be destroyed and provided with a flue extending from the bottom of the pot upwardly and 75 open at its lower and upper ends, a burner arranged at the lower end of said flue and a deflector arranged above the upper end of the flue and mounted thereon. 80

5. A refuse incinerator comprising a combustion chamber, a pot arranged in the combustion chamber and adapted to receive the material to be destroyed and provided with a flue extending from the bottom of the pot upwardly and open at its lower and upper 85 ends, a burner arranged at the lower end of said flue, a deflector arranged above the upper end of the flue and means for supporting 90 said deflector on said flue consisting of a cross bar mounted on the inner side of said flue and a stem rising from said cross bar and connected at its upper end with said deflector. 95

6. A refuse incinerator comprising a combustion chamber, a pot arranged within the chamber and having a flue rising from the bottom thereof and a channel arranged diametrically on the underside of the bottom and opening into the lower end of said flue and a burner having a horizontal delivery 100 pipe arranged in said channel and provided with a delivery nozzle which opens upwardly into the lower end of said flue. 105

7. A refuse incinerator comprising a cylindrical combustion chamber, a cylindrical pot arranged in said chamber and adapted to receive the material to be destroyed and provided centrally with a flue extending upwardly from the bottom and having an external flange at its upper edge which engages the inner side of the combustion chamber and provided with an annular row of notches for the passage of vapors, and a burner arranged at the lower end of said flue. 110
